UNITED STATES PATENT OFFICE

ARTHUR K. BECKWITH, OF DOWAGIAC, MICHIGAN, ASSIGNOR TO THE ESTATE OF P. D. BECKWITH, INCORPORATED, OF DOWAGIAC, MICHIGAN.

DESIGN FOR A COOKING STOVE OR RANGE.

42,102.

Specification for Design.

Patented Jan. 23, 1912.

Application filed October 6, 1911. Serial No. 653,291. Term of patent 14 years.

To all whom it may concern:

Be it known that I, ARTHUR K. BECKWITH, a citizen of the United States, residing at the city of Dowagiac, in the county of Cass and State of Michigan, (whose post-office address is Dowagiac, county of Cass, and State of Michigan,) have invented a new, original, and ornamental Design for a Cooking Stove or Range, of which the following is a specification, reference being had to the accompanying drawing, forming a part thereof.

The figure is a perspective view of a cooking stove or range, showing my new design.

I claim:

The ornamental design for a cooking stove or range, as shown.

In witness whereof, I have hereunto set my hand in the presence of two witnesses.

ARTHUR K. BECKWITH.

In presence of—

G. S. PIPER,
ROBERT N. NORTON.
